UNITED STATES PATENT OFFICE

EDWARD A. PORTER, OF BRATTLEBORO, VERMONT

HUMIDOR

Application filed May 12, 1928. Serial No. 277,813.

The invention relates to devices for humidifying air, and especially one automatically controlled by the degree of humidity in the circumambient air and applicable to use in show-cases, although various features thereof are applicable in numerous other situations, as will be readily understood from the disclosure herein.

It is a particular object of the invention to present an appliance of this character which will be operative to rapidly raise the humidity of air in the show-case, while yet being quite compact and not occupying a great amount of room. It is adapted to be suspended in the show-case in the same manner as, and to replace, other devices now in use which require numerous units throughout the length of the show-case, occupying valuable space and obstructing the view of customers inspecting the goods. It is a particular aim of the invention to provide a device of this character which may be mounted either within or beneath the floor of the case and maintained in operation over long periods of time with a minimum of service attention. It also enables the removal of operative parts in the case in a very simple manner.

A further important aim of the invention is to attain a high rate of water vaporization by novel structure and correlation of parts. A further important aim is to present a novel assembly of parts which, in addition to enabling the easy removal and replacement of the operative units in the device, will also lower manufacturing costs and attain great compactness in the units necessary for a device of this character. Incident to this, in order to afford the rapid supply of water to vaporizing surfaces within a small area, a mechanical device is employed for moving the surfaces upon which water is exposed, and it is an important aim to enable the ready removal of the reservoir carrying this movable apparatus without requiring dismounting or removal of operative connections.

An especially important purpose of the invention is to enable the adaptation of a single mechanical structure to use either as an installable unit adapted to be suspended in ordinary show-cases, or as a built-in unit be-

neath the show-case and invisible ordinarily. Additional objects, advantages and features of invention reside in the construction, arrangement and combination of parts involved in the embodiment of the invention, and method as used, as will be more readily understood from the following detailed description and accompanying drawings, in which,

Figure 1 is a vertical longitudinal sectional view of one embodiment of the invention.

Figure 2 is a top view thereof with the top of the case broken away at each end, and the intermediate horizontal partition removed also at each end.

Figure 3 is a fragmentary horizontal section showing the mounting of the water level pointer.

Figure 4 is a fragmentary side elevation of the device showing the filling conduit and water level indicator mounting.

Figure 5 is an end elevation.

Figure 6 is an enlarged cross sectional view showing the transverse partition.

Figure 7 is a fragmentary cross sectional view in the same plane and direction, with the transverse partition removed.

Figure 8 is an end elevation showing a modified form of casing.

Figure 9 is a perspective view of a show-case showing the manner of installation of the last-named modification of the case and coordinated show-case structure.

Figure 10 is a top view of the structure of Figure 9.

Figure 11 is a detail of the humidistat hydrostat by which operation of the humidor is controlled.

Figure 12 is a fragmentary cross section of the humidistat.

Figure 13 is a detail of the corner post of the show case.

Figure 14 is a cross section thereof.

Figure 15 is a detail of one end of the humidistat.

Figure 16 is a perspective showing a show case within a humidistat and a humidifier therein, electrically connected.

There is illustrated a humidifier comprising

ing an elongated sheet metal case 10, of rectangular form, throughout the major portion of which a horizontal partition 11 is extended, joined to the sides and terminating at the removable front end cover 12 of the case. At its inner end the horizontal partition 11 is inclined upwardly as at 13, to provide ready access of air passing under this partition to the circular fan-intake opening 14 formed in a transverse partition 15 located immediately at the inner extremity of the partition 11, and closing the case snugly except for small openings 16 (see Fig. 6) at one upper and one lower corner to permit an insulated electric conductor cable and a flexible shaft to be led snugly therethrough, as will be described, and a fan outlet opening 17 in an upper corner. The space beneath the partition 11 may be made watertight to serve as a reservoir, but preferably a reservoir pan 18 is slidable in the space beneath the partition 11 from the end at which the closure 12 is located.

The reservoir 18 as well as the case and partition parts may be formed of sheet steel, or other metal. The reservoir is formed with sides which approach as closely as may be to the under side of the horizontal partition 11 and at the ends is lower than at the sides, to permit free passage of air beneath the partition 11. The front end cover 12 is provided with a number of foraminations 19 communicating with the case below the partition 11 and preferably the cross sectional area of these in the aggregate is smaller than the clear way through the opening 17 of the transverse partition before mentioned, as well as being adapted to substantially restrict movement of air by the fan whereby a vacuous condition may be produced over the reservoir, as will be explained. Adjacent the forward end of the reservoir 18 a plain horizontal roller 20 is mounted transversely therein, while adjacent the rear end a corresponding roller 21 is mounted having an extended flange 22 at one side formed with spur-teeth 23 at the periphery, and so mounted as to project above the side of the reservoir slightly. An endless water-spreading belt 24 is mounted upon these rollers to travel thereon, and if desired, any approved means for maintaining the tension of the belt may be employed. The gear portion 23 is closely adjacent the side of the reservoir, and is adapted to mesh with a gear 25 mounted on a vertical axis upon the side of the case 10, which may be pressed out to receive part of the gear, as shown in Figure 2. The gear 25 is located immediately over the side of the reservoir, projecting inwardly thereover to mesh with the gear 23 of the roller 21, and it will be seen that under sliding movement of the reservoir as it is removed or replaced, the gear 23 may move into mesh with the gear 25 without requiring special manipulations un-

der the simple movement of the reservoir to and from its proper position in the case 10.

A lever rod 26 is pivoted intermediately of its length upon the side of the reservoir opposite the gear 23, extending for the most part in close parallel relation to this side of the reservoir, and having affixed to its front end a transverse float 27 by which the rod will be operated as a lever under rise and fall of the water level in the reservoir. The rod projects rearwardly of its point of pivotal support a distance, and when the reservoir is empty the rear end portion extends upwardly at an incline slightly above the top of the reservoir, and is also offset inwardly from the side of the reservoir to extend over the belt 24 a distance. On the adjacent side of the case 10 a shaft 28 is mounted revolvably, extending through the side of the case and carrying on its outer end a pointer 29.

The inner part of the shaft 28 is cranked as at 30, the crank being located forwardly of the axis of the shaft, and the pointer being projected rearwardly so that its weight will hold the crank in elevated position except when the crank is pressed upon by the rear end of the rod 26. The downward movement of the pointer may be limited in any suitable manner, and on the side of the case an index mark 31 is formed which will be alined with the pointer when it has been operated through the agency of the rod 26 and float 27 by the rise of water to a predetermined desired normal water level. It will be seen that the reservoir may be withdrawn at any time without interference between the rod 26 and the crank 30, and if returned in empty condition (which is the proper method) the parts will automatically assume proper operative relation, the rear end of the rod passing over the crank 30 and coming into engagement therewith when the reservoir is at the inner limit of its movement. Thus no special manipulations are required for removal and replacement of the reservoir and the operative devices thereon.

At the side of the case 10 beside the motor fan chamber a short pipe 70 is secured to the side of the case, having one end turned inwardly and extended through the side of the case over the reservoir 18 immediately under the upwardly inclined portion 13 of the partition 11, as may be seen in Figures 4 and 6. The pipe is extended longitudinally toward the rear end of the case 10 and inclined upwardly, and provided with a hinged cover 71, the end of the pipe being exposed as may be desired conveniently for permitting water to be poured therein from the rear of the show-case without difficulty, to replenish the supply of water in the reservoir. The inner end of this pipe clears the reservoir and other parts so that it does not inter-

fere with removal and replacement of the reservoir, as may be understood.

It will be noted that the cover 12 is not perforated in its upper part above the partition 11, but each side of the case 10 is formed with a longitudinal series of vent apertures 31. Within the space rearwardly of the transverse partition 15, there is mounted an electric motor 32, having its shaft arranged longitudinally of the case 10. At the forward end the shaft projects sufficiently to receive the impeller or fan proper 33 of a rotary fan, which is provided with a cylindrical circumscribing stationary casing 34 fitting against the top and sides of the case 10 and having a perimetral opening 48 adjacent the opening 17 of the partition 15. A plate 35 forms the rear side of the casing 34, the forward side of this casing being entirely open. The plate 35 is extended at the top to provide corner portions 36 to fit snugly the top and side of case 10 as a means of centering the fan casing. This corner extension may be found essential only at one corner. The casing of the fan is attached to the casing of the motor 32 by means of brackets 37. Suitable supports are provided at 38 for centering the motor centrally in the case 10, and securing it in place when thrust inwardly until the fan casing abuts the transverse partition 15. The rear end of the motor shaft is provided with a worm 39, and mounted suitably upon the case of the motor or otherwise, for ready removal, there is a worm gear 40 having connected thereto a flexible shaft 41 suitably enclosed and extended downwardly and forwardly in the case 10 through the partition 15, thence upwardly, where it is connected to the spur gear 25 before described. The leads to the motor are shown entering at 45, and the leading-in cables at 46, which may be connected to any electrical outlet of standard service type by means of the usual plug. Included in a circuit of the motor, however, there is a small heater unit 47 of any usual construction. That is to say, the heater is connected in series with the motor, being included in one side of the circuit to the motor, as will be readily understood. Also included in the circuit to the motor there is shown in Figure 9 an automatic regulator 50, responsive to the humidity of the air in the show-case in such manner that when the humidity is above a desired degree, the circuit to the motor will be automatically cut out, and when it falls below a predetermined desired minimum, the circuit will be closed by the device and the humidifier operated to rectify the condition. As the casing fits snugly against the top and two sides of the casing 10 and the partition 15, it prevents the escape of air except the outlet opening 48 in the fan casing and opening 17 in partition 15. Thereby, under operation of the fan, air forced outwardly by

the impeller will pass through the opening 48 and into the space in advance of the extension 36 of the rear plate of the fan casing, and thence forwardly through the opening 17 in the transverse partition, to the distributing chamber or space 49 from whence the air will be permitted to escape equally through the apertures 31 before mentioned at each side of the case 10. Air can only enter the fan casing from the space over the reservoir.

In Figures 8 to 10 inclusive the same construction in the humidifier device is involved, but the case 10' is modified from the construction previously described so that instead of a series of small openings in the cover 12, a single opening 52 is formed in the head 12' corresponding to the cover 12, and on each side of the case 10' in place of the multiplicity of small apertures 31, two large circular openings with circumscribing flanges are formed at 53. This device is incorporated beneath the show-case, as shown in Figures 9 and 10 with its rear end exposed flush with the baseboard at the rear of the show-case. From the inlet opening 52 a conduit 54 is extended to a circular screened opening 55 formed in the floor of the show-case, while from each of the lateral outlets 53 conduits 56 are led, each to a respective corner post 57 in the rear corners of the case. Each of these corner posts is tubular, having two planiform sides at right angles to each other and a connecting curved side, so that the complete device corresponds to the usual quarter-round, used in the corners of showcases. In the curved face of each post a multiplicity of longitudinally spaced apertures 58 are formed, in the shape of key-slots, so that standard fixtures for mounting the shelves may be used therein in the same manner as they are now used in corner pieces of angle iron having such slots therein. Thereby the corner posts serve the double function of a ventilating conduit and distributor manifold, and also a shelf support, the same apertures which vent the humidified air to the case serving as the rests in which the shelf fixtures may be engaged in a familiar way.

In Figures 11 and 12 there is illustrated in detail the automatic control device by which the humidity of the case is maintained at any desired degree suitable to the character of the goods displayed. In this instance, it comprises a central bar 60 which may be formed of channel iron or otherwise as desired, and is provided at each end with a T-head 61 by which flanges are formed at the upper and lower sides of the bar, as shown in Figure 11. Sprung into bowed form and having its ends set against respective flanges at each end of the bar there is an element 63 of hygroscopic wood, outwardly of which there is laid a thin band of metal 64, not cemented to the wood but longitudinally slotted closely adjacent

its extremities. Commonly engaged through the two bows at each end, there is a bolt 65 by which the ends of the bows are prevented from accidentally becoming displaced laterally or otherwise from the bar 60, the slots 5 in the metal band permitting the metal to bow upwardly and draw inwardly at each end when the wood expands sufficiently to increase the curvature of the bow and separate the middle portions from the bar. The band 10 64 does not necessarily touch the bar, as will be understood. Engaged adjustably through the central portion of each bow, there is a contact screw 66 projecting inwardly so that 15 the opposed screws may contact when the bows are the least affected by humidity, and engaged through the bar 50 there is a sleeve 67 of non-conducting material, serving as a guide for the inner ends of the screws. Respective wires 68 forming one side of the circuit to the motor 32 are connected to the screws. The structure of Figure 11 may be 20 enclosed in any suitable case, as shown in Figure 9 adapted for location as desired in 25 a show-case, or elsewhere, in the present instance the closure case for the humidistat having suction pads 69.

In the operation of this device, when the 30 humidity of the case decreases sufficiently to cause the humidistat to operate and close the circuit to the motor, operation of the fan and the heater unit will occur, the fan drawing air longitudinally through the reservoir chamber at the same time that the belt 24 is operated 35 to expose freshly wetted surfaces to the air current. By making the connections so as to move the upper reach of the belt rearwardly, retention of the reservoir and operative parts thereon in operative position is assured. By 40 reason of the limiting action of the intake through the cover 12, a vacuous condition will be produced enhancing the vaporizing efficiency of the device very materially. The partition 11 is located at the lowest practicable elevation with respect to the reservoir and entrance belt 24, so that the air passing through the reservoir chamber will be held in a path closely adjacent the belt, further enhancing the vaporization of the water by 45 50 the air moving therein. The air expelled from the fan casing passes to the distributor chamber and escapes through the apertures 31. In the form shown in Figures 8 to 10 the screen over the opening 55 serves as a retarding means, and the discharged air passes through the tubes 56, by which it is led to the distributor corner posts, as before explained.

The cable 69 by which the heater unit is 60 connected in series with the motor is extended through the aperture 16 before mentioned, in the upper corner of the transverse partition 15, and laid loosely in the distributing chamber with sufficient slack to permit withdrawal of the motor readily when necessary.

The wire is led to a notch in the extreme front end of the partition 11, and extends inwardly a distance to the heater unit 47, so that when the reservoir 18 is to be removed, it may be drawn out a distance without being obstructed by the wire or the heater unit, 70 until the heater unit is well beyond the end of the case, when the heater unit may be lifted out of the reservoir and laid upon the partition 11 until it is necessary to return 75 it to the reservoir.

In removing the fan, it is only necessary ordinarily to use one bolt to secure the fan in place, removal of which permits withdrawal of the motor and fan casing as a unit, 80 after disconnecting the flexible shaft 41. It may be seen that mere introduction of the motor and fan casing and securing the motor in place will insure the completion of the air duct necessary for the intake of air from the 85 reservoir chamber and discharge from the distributing chamber without use of any couplings or special fastenings or joints. The device is adapted to be made in a size but little larger than that shown in the drawings, 90 and has been made and found to operate efficiently in a size twice that of the showing in the drawings.

It will be understood that there are modifications of structure within the scope of the 95 claims which may be made without departing from the spirit of the invention, and that features of one form of the device may be combined with those of another in accordance with disclosures herein to obtain the full- 100 est advantages of the invention.

I claim:

1. A humidifier comprising a casing having a reservoir chamber and a distributing chamber, a water spreading element mounted 105 for movement in the reservoir chamber, an air impeller having an intake communicating with the reservoir chamber and an outlet to the distributing chamber, said reservoir chamber having an inlet substantially restricted with respect to the capacity of the air impeller, said distributing chamber having vent means of capacity substantially greater than that of the inlet aforesaid.

2. A humidifier comprising a case having a 115 water vaporizing chamber and an air distributing chamber, a reservoir slideable into the first chamber for removal and replacement, a water spreader operative therein, and means to operate the spreader including a driving gear mounted on the case, and a driven gear revolvably mounted on the reservoir movable with the reservoir to and from the driving gear, the engaged position of the gears coinciding with the operative position 120 of the reservoir.

3. A humidifier comprising an elongated case having a medial longitudinal partition therein stopping intermediately of the length of the case, an air inlet being provided at the 130

lower side and an air outlet at the upper side of said partition, a reservoir in the chamber at the lower side of the partition, the inner part of the partition being terminally inclined upward a distance, a transverse partition having a central opening immediately adjacent the extremity of said terminal inclined part and having a port therethrough communicating with the upper space beside the first named partition, a fan device including a circumscribing case closed at the outer side and open at the inner side next the longitudinal partition, and movable slidably into the first named case to abut the transverse partition opposite the first named partition, the fan case having a discharge in communication with the space over the longitudinal partition.

4. A humidifier comprising a case having a reservoir chamber and a slidable reservoir movable into the chamber, a water distributor movably mounted in the reservoir, operative means for the distributor including a gear revolvably mounted on the reservoir and exposed above the top of the reservoir, a gear revolvably mounted on the case and having a portion interposed in the path of movement of said exposed portion of the first named gear incident to sliding movement of the reservoir, and operative means for the second named gear.

5. A humidifier comprising an elongated case adapted to be secured in a show case with a rear end toward the access opening of the show case, a motor and air impeller device mounted removably in the said rear end, upper distributor and lower reservoir chambers formed in the front portion of the humidifier case, a reservoir longitudinally slidably in the reservoir chamber for removal and replacement at the front end of the humidifier case, a refill conduit having a discharge end opening into the upper side of the reservoir space, and having an outer end exposed at the rear end of the humidifier case, and means exteriorly of the humidifier case to indicate the water level in the reservoir.

6. In a humidifier, a case having a vaporizing chamber and a distributing chamber, a reservoir slidable in and out of the vaporizing chamber, an impeller drawing from the vaporizing chamber and discharging into the distributing chamber, an electric motor for the impeller, and an electric heater separably mounted in the reservoir for removal therewith and in series circuit with the motor.

7. A humidifier comprising a casing having evaporating means, a fan and motor therein for drawing air to the evaporating means and forcing it to an outlet, and lateral conduits leading from said outlet and having vertical apertured extensions forming their discharge outlets.

8. A humidifier comprising a casing having evaporating means, a fan and motor

therein for drawing air to the evaporating means and forcing it to an outlet, lateral conduits leading from said outlet and having vertical apertured extensions forming their discharge outlets, and a humidistat having contacts actuated thereby and in electric connection with said electric motor. 70

In testimony whereof I affix my signature.
